UNITED STATES PATENT OFFICE

SIMON CANTOR, OF NEW YORK, N. Y., ASSIGNOR TO LA BELLE SPECIALTY CO., INC., A CORPORATION OF NEW YORK

DESIGN FOR A LAMP BASE OR ARTICLE OF ANALOGOUS NATURE

Application filed October 16, 1930. Serial No. 37,270. Term of patent 3½ years.

To all whom it may concern:

Be it known that I, SIMON CANTOR, a citizen of the United States of America, and a resident of the city, county, and State of New York, have invented a new, original, and ornamental Design for Lamp Bases or Articles of Analogous Nature, of which the following is a specification, reference being had to the accompanying drawing, forming a part hereof.

In the drawings:

Figure 1 shows a front perspective view of the lamp base or article of analogous nature; and Figure 2 is a diagrammatic side elevational view of the same.

The rear of the lamp base is like the front, except that the human figure is viewed from behind.

I claim:

The ornamental design for a lamp base or article of analogous nature substantially as shown and described.

SIMON CANTOR.
